US00D990468S

(12) **United States Design Patent** (10) **Patent No.:** **US D990,468 S**
(45) **Date of Patent:** **** Jun. 27, 2023**

(54) **SMART WATCH**

(71) Applicant: **OnePlus Technology (Shenzhen) Co., Ltd.**, Shenzhen (CN)

(72) Inventors: **Ruiping Dong**, Shenzhen (CN); **Haoran Liu**, Shenzhen (CN); **Xinyi Jiang**, Shenzhen (CN)

(73) Assignee: **ONEPLUS TECHNOLOGY (SHENZHEN) CO., LTD.**, Guangdong (CN)

(**) Term: **15 Years**

(21) Appl. No.: **29/765,832**

(22) Filed: **Jan. 12, 2021**

(30) **Foreign Application Priority Data**
